CHESTER M. SEWELL, OF PORTERVILLE, CALIFORNIA

ARCH SUPPORT

Application filed July 6, 1931. Serial No. 548,861.

My invention relates to remedial devices for the treatment of foot troubles, and has particular reference to corrective shoes or corrective inner soles for the restoration of fallen arches.

The higher side of the major or longitudinal arch of the normal human foot is adjacent the inner longitudinal side of the foot, i. e., the side of the first metatarsal bone and the apex of the arch is under the tarsus region of the foot. The arch slopes laterally downward towards the outer side of the foot, i. e., the side of the fifth metatarsal bone. In my description and claims to follow, the term "outer longitudinal side", applied to either the foot or the corrective device, will refer to the side of the fifth metatarsal, and "inner longitudinal side" will refer to the side corresponding to the first metatarsal bone of the foot.

The usual type of arch support is designed to correct a weak or fallen arch by presenting a suitable elevation or "arch" complementary to the normal arch of the foot, i. e., the arch support is highest along the inner longitudinal side of the foot and slopes laterally downward towards the outer longitudinal side in a configuration complementary to the natural contours of the sole of the foot. The theory behind such a construction is that when the bones of the arch are held in their normal positions to avoid unnatural stresses, irritated interior portions of the foot are healed and the arch is strengthened. I shall refer to this underlying idea as the "theory of direct support" in order to emphasize the principle of indirect support which is fundamental to my invention, and which sharply distinguishes my invention from the usual device.

A common objection to treatment by direct support is that when the arch is relieved of weight by a complementary elevation placed under the foot, the muscles and ligaments of the foot may tend to become adjusted to the

lessened demand upon them instead of building up strength and tone to hold a normal arch under natural conditions.

In the course of developing an arch support to be free from this objection, and in studying methods of hastening the correction of such foot troubles, I have discovered the efficacy of employing a supporting elevation or arch disposed just the opposite from the position of the usual "complementary" type of support, that is the arch I employ extends longitudinally of the foot along the outer longitudinal side and slopes laterally downward towards the inner longitudinal side of the foot. The principle involved may be called that of indirect support, because the arch of the foot is not directly supported.

While the cause of the increased curative effects of my device over the usual construction is not readily analyzed into individual factors of definite relative weight, nevertheless, certain advantages of my method of treating arch troubles may be pointed out.

In the first place, by virtue of the disposition of the arch of my support, the weight-bearing contact of the intermediate portion of the foot is along the outer longitudinal side as nature intended, instead of being distributed under the arch of the foot by the usual "complementary" arch support. As a result, circulation of the blood through the muscles of the plantar region of the foot is not unduly restricted by unnatural pressure under the arch bone.

In the second place, my support tends to rock the foot laterally inward, thereby causing a beneficial reaction of the muscles similar to that involved in corrective foot exercises in which the foot is turned to throw the weight on the outer side. This muscular reaction encourages the blood circulation and builds up the muscles required to support the bones of the arch, while the lateral tilting of the foot seems to relieve the strain on those

irritated interior surfaces that are incident to fallen arches.

In conjunction with my special arch, I find that a resilient elevation or cushion under the ball of the foot may be employed to advantage. While this auxiliary cushion is desirable and of proven value, it is not to be understood as indispensable in obtaining the previously indicated benefits ascribed to my form of longitudinal arch. When this cushion is positioned to elevate the forward ends of the second and third metatarsal bones, it exerts a beneficial influence which extends to the first metatarsal bone and which augments the beneficial effects of the primary longitudinal support. The cushion also has a moderating effect on the tendency of the longitudinal support to tilt or rock the foot laterally, that is, it serves as a bearing point which may be used, especially in the initial stage of treatment, to assist the muscles to resist the tilting action. It has been found, also, that such a cushion straightens the toes in opposition to any tendency of the phalanges to be pulled upward or downward by the unnatural strain on ligaments commonly occasioned by displaced bones. My form of longitudinal arch in combination with such a cushion constitutes a complete corrective device applicable to various degrees of arch trouble.

While my invention may be incorporated in a shoe construction, it is particularly applicable to an arch support manufactured as a separate inner sole, and will be so described for the purposes of disclosure.

The objects and advantages of my invention will be apparent from the detailed description to follow, taken with the drawing, in which:

Fig. 1 is a plan view of the left arch support, with the bones of the foot indicated by dotted lines;

Fig. 2 is a side elevation of the arch support, taken from the right-hand side;

Fig. 3 is a front end elevation;

Fig. 4 is a rear end elevation; and

Fig. 5 is a transverse section taken as indicated by the lines 5—5 of Fig. 2.

The position of the various bones of the foot with relation to the inner sole, generally designated 10, is indicated by Fig. 1. The first to the fifth metatarsal bones are numbered with Roman numerals I, II, III, IV and V respectively. The two elevated portions of the inner sole are the longitudinal arch 11 and the forward cushion 12. It will be noted that the longitudinal arch slopes laterally downward from the outer longitudinal side of the foot under the fifth metatarsal bone towards the opposite side of the foot. The extent of this arch may be varied both longitudinally and laterally, but for the average case of foot trouble, I prefer the configuration shown. Beginning forward

substantially at the metatarsal joint 13 between the fifth metatarsal bone and its corresponding phalange 14, the arch extends rearward to the posterior end of the cuboid 15, and slopes down laterally towards the first metatarsal bone. The cushion 12 is placed under the ball of the foot, preferably in a relatively central position to support the second and third metatarsal joints, as shown.

The inner sole 10 may be of rigid or semi-rigid metal construction, but I prefer to fabricate it from flexible material, such as leather. An upper ply or leather inner sole 16 overlies and is cemented to a lower layer of leather 17, the two being cut to a suitable configuration to fit inside a shoe. Interposed between, and cemented to, the two plies 16 and 17, is a cushion, or core, 18 of rubber, or a like material, which forms the body of the longitudinal elevation or arch 11. A refinement in this construction, which is desirable but not indispensable, is a flange 19 turned upward along the outer longitudinal side of inner sole 10 adjacent arch 11, for the purpose of preventing the foot working over the outside edge of arch 11. This flange may be formed by simply extending the two plies above and beyond core 18, as indicated by Fig. 5.

Forward cushion 12 may be constructed with a permanently encased piece of rubber, as in the case of core 18, but preferably is made to be readily adjusted to meet individual requirements. To this end, an arcuate line of stitching 20 may define an open pocket 21 between the two plies 16 and 17 at the forward end of inner sole 10, in order to receive a removable core or cushion generally designated 22. This core is preferably circular, with tapered edges, and may comprise multiple relatively thin rubber disks 23, detachably held together by glue.

Preferably the bottom of the inner sole is faced with a thin sheet of rubber 24 to insure adequate frictional engagement with the inside of the shoe.

It is obvious that the whole device may be molded of rubber in one piece or may consist of a suitably shaped piece of rubber with a leather facing on the upper surface.

The above described inner sole is the preferred form of my invention, but the principles I have discovered and disclose may be embodied in other forms structurally divergent from the described arch support, and I reserve the right to all such embodiments as properly come within the scope of my appended claim.

Having described my invention, I claim:

An arch support comprising: a flexible inner sole having a pocket underlying the ball of the foot; a rubber cushion incorporated in the inner sole, forming a longitudinally extending arch support tapering laterally downward from the outer longitudinal side

of the foot towards the inner longitudinal side of the foot; a flange integral with the inner sole extending upward along the outer longitudinal side of the inner sole adjacent 5 said arch; and a plurality of rubber disks of different diameters in said pocket of the inner sole, said disks being cemented together face to face in concentric relation and arranged in a progressive series with the small- 10 est disk uppermost.

In witness that I claim the foregoing I have hereunto subscribed my name this 25th day of June, 1931.

JOHN H. GOLDEN.
